(57) **CLAIM**

The ornamental design for a baby memory box, as shown and described.

DESCRIPTION

FIG. 1 is a front perspective view of a baby memory box, showing my new design, showing component 1 in an open configuration;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view thereof, showing component 2;

FIG. 10 is a rear perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof;

FIG. 16 is a bottom view thereof;

FIG. 17 is a front perspective view thereof, showing component 3 in an open configuration;

FIG. 18 is a rear perspective view thereof;

FIG. 19 is a front view thereof;

FIG. 20 is a rear view thereof;

FIG. 21 is a left side view thereof;

FIG. 22 is a right side view thereof;

FIG. 23 is a top view thereof;

FIG. 24 is a bottom view thereof;

FIG. 25 is a front perspective view thereof, showing component 4 in an open configuration;

FIG. 26 is a rear perspective view thereof;

FIG. 27 is a front view thereof;

FIG. 28 is a rear view thereof;

FIG. 29 is a left side view thereof;

(Continued)

FIG. 30 is a right side view thereof;
 FIG. 31 is a top view thereof;
 FIG. 32 is a bottom view thereof;
 FIG. 33 is a front perspective view of component 5 thereof;
 FIG. 34 is a rear perspective view thereof;
 FIG. 35 is a front view thereof;
 FIG. 36 is a rear view thereof;
 FIG. 37 is a left side view thereof;
 FIG. 38 is a right side view thereof;
 FIG. 39 is a top view thereof;
 FIG. 40 is a bottom view thereof;
 FIG. 41 is a front perspective view of component 6 thereof;
 FIG. 42 is a rear perspective view thereof;
 FIG. 43 is a front view thereof;
 FIG. 44 is a rear view thereof;
 FIG. 45 is a left side view thereof;
 FIG. 46 is a right side view thereof;
 FIG. 47 is a top view thereof;
 FIG. 48 is a bottom view thereof;
 FIG. 49 is a front perspective view of component 7 thereof;
 FIG. 50 is a rear perspective view thereof;
 FIG. 51 is a front view thereof;
 FIG. 52 is a rear view thereof;
 FIG. 53 is a left side view thereof;
 FIG. 54 is a right side view thereof;
 FIG. 55 is a top view thereof;
 FIG. 56 is a bottom view thereof;
 FIG. 57 is a front perspective view of component 8 thereof;
 FIG. 58 is a rear perspective view thereof;
 FIG. 59 is a front view thereof;
 FIG. 60 is a rear view thereof;
 FIG. 61 is a left side view thereof;
 FIG. 62 is a right side view thereof;
 FIG. 63 is a top view thereof;
 FIG. 64 is a bottom view thereof;
 FIG. 65 is a front perspective view of component 3 thereof, the front perspective view of component 4 being identical;
 FIG. 66 is a rear perspective view of component 3 thereof, the rear perspective view of component 4 being identical;
 FIG. 67 is a front perspective view of a baby memory box, showing components 1, 2, 3, and 4 in a combined state and open configuration;
 FIG. 68 is a front view thereof;
 FIG. 69 is a rear view thereof;
 FIG. 70 is a top view thereof;
 FIG. 71 is a bottom view thereof;
 FIG. 72 is a front perspective view thereof, showing components 3 and 5 in a combined state and open configuration;

FIG. 73 is a front perspective view thereof, showing components 4, 7, and 8 in a combined state and open configuration;
 FIG. 74 is a rear and side view of component 2;
 FIG. 75 is an exploded front view thereof, showing components 3, 4, 5, 7, and 8 in a combined state and partially open configuration; and,
 FIG. 76 is an exploded front view thereof, showing components 2, 3, 4, 5, 7, and 8 in a combined state and partially open configuration.

The broken lines are shown for the purpose of illustrating both parts of the article as well as environmental subject matter. None of the broken lines form part of the claimed design.
